UNITED STATES PATENT OFFICE.

JAMES W. HUBBARD, OF CHICAGO, ILLINOIS.

PRINTING MACHINE.

Application filed July 18, 1921, Serial No. 435,498. Renewed January 8, 1926.

This invention relates to printing machines adapted to print tickets used by railroads and more specifically relates to such a machine which simultaneously prints and records detailed data regarding each ticket printed. In accordance with present railroad practice, each ticket office maintains large racks in which are placed a large supply of railroad tickets reading from the 10 place of origin to a very great number of different destinations, not only along its own lines, but also along the lines of other railroads over which a given journey must be continued. Large supplies of these various 15 printed tickets for each station are also maintained in reserve. This novel machine obviates the necessity for the ticket office supply and the reserve supply.

This novel printing machine is adapted 20 quickly to print a ticket form upon a strip of paper which form shows the place of origin, the name of the issuing company, interline railroad, and the usual general conditions such, for example, as the provision 25 for continuity of passage and the time of commencement. It also selectively prints, upon the same portion of the strip upon which such form appears, certain specific indicia such as the date of issuance, destination, amount of fare, names of interline 30 railroads, if any, i. e., railroads over which the given journey must be continued and a serial number for each individual ticket.

The parts of this novel machine may be 35 generally referred to as the ticket printing part and the recording part. The ticket produced by this machine is provided with an integral but easily separable portion commonly known as the check. In other 40 words, a ticket comprises a check and a ticket proper, the check being adapted to be torn from the ticket proper along a line of scoring, by the first conductor in accordance with common railroad practice. The 45 record produced by this machine is retained within the machine casing and may be detached at intervals by the auditing officials of the railroad company issuing the ticket. The record is printed on a substantially 50 continuous strip of paper. This record strip has data printed thereon every time a ticket is printed. In the preferred embodiment of the invention here shown, such record data comprises the total mileage covered by the issued ticket, the destination thereof, the issuing railroad and continuing

railroads, if any, and the apportionment of the fare earned by each railroad, and apportioned war tax.

The object therefore of this invention is 60 to provide an improved device for printing railroad tickets.

A more specific object is to provide a machine for printing railroad tickets while simultaneously printing an audit record 65 giving detailed data in regard to each ticket printed.

Other objects of the invention will more fully appear from the following description and the accompanying drawings and 70 will be pointed out in the annexed claims.

In the accompanying drawings, there has been disclosed a structure designed to carry out the objects of the invention, but it is to be understood that the invention is not 75 confined to the exact features shown as various changes may be made within the scope of the claims which follow:

In the drawings:

Figure 1 is a view in elevation of the right 80 end of the machine and standard with the casing omitted;

Figure 2 is a view in front elevation of the machine without the casing;

Figure 3 is a plan view of the machine 85 without the casing;

Figure 4 is a vertical sectional view of the line 4-4 of Figure 3, i. e., adjacent the right or ticket end of the machine, and showing the platen arm in elevated position;

Figure 5 is a view similar to that of Figure 4, but with the platen arm down in printing position;

Figure 6 is a view in elevation of the left 90 or audit record end of the machine;

Figure 7 is a vertical longitudinal sectional view on the line 7-7 of Figure 4;

Figure 8 is a vertical cross sectional view 100 on the line 8-8 of Figure 2, and showing in detail the inking devices, and the ticket cutting and pick-up;

Figure 9 is a similar view on the line 9-9 of Figure 2, showing the printing drum actuating parts;

Figure 10 is a detail view of the actuating parts shown in Figure 9;

Figure 11 is a detail view similar to that of Figure 10 but with the parts in a different 110 position;

Figure 12 is a vertical longitudinal sectional view on the line 12-12 of Figure

- 5, showing the dating device and the ticket form type in printing position;
- Figure 13 is a partial horizontal view in section on the line 13—13 of Figure 12
- 5 showing the ticket form type and dating device;
- Figure 14 is a view in plan of a portion of the index wheel;
- Figure 15 is a detail sectional view of the
- 10 clamping means for feeding the paper strip with the clamping parts in open position;
- Figure 16 is a view similar to that of Figure 15 but showing the parts in clamping position;
- 15 Figure 17 in a detail view showing the mounting of the cutting knife and the front platen on the platen arms;
- Figure 18 is a detail view of the means for locking the knife and front platen arm
- 20 in operable position on the platen arms;
- Figure 19 is a detail view, partially in section, of the inking means for the printing rolls and the ticket pickup;
- 25 Figure 20 is a view in front elevation of the ticket cutting knife;
- Figure 21 is a sectional detail of the ticket cutting knife and shearing block;
- Figure 22 is a detail view in front elevation of the shearing block;
- 30 Figure 23 is a detail view of the clutch, clutch-operating parts, and drive;
- Figure 24 is a view in side elevation of the same;
- 35 Figure 25 is a plan view of the same;
- Figure 26 is a view on the line 26—26 of Figure 25;
- Figure 27 is a view in front elevation of the paper strip clamping means;
- 40 Figure 28 is a vertical cross-sectional view through the casing and showing the audit type wheel and manner of retention of the audit or record strip in the casing;
- Figure 29 is a view in front elevation showing a portion of the machine end casting adjacent the right end of the machine;
- 45 Figure 30 is a detail view of a modified form of type-bar mounting; and
- Figure 31 is a view in front elevation of the same.
- 50 In this selected embodiment of the invention, the machine is supported by a standard formed of relatively light tubular metal and having four legs 35 joined by the top rods 36 and suitably braced by the reinforcing rods 37. A casing 38 of sheet metal (see Figures 28 and 29) enclosed the parts of the machine with the exception of the rotatable dial 182 by means of which particular stations or destinations may be selected to be printed and an operating crank 41 and handle 42 by means of which the machine may be manually operated. Across the front of the machine, the casing is provided with doors 43 having locks 44 permitting only authorized access to the interior
- of the casing. The casing extends below the top rods 36 upon which are supported the plate frames 45, 46, 47 and 48 bearing the operating parts. The casing downwardly extends and terminates adjacent the reinforcing cross rods 37 and thus provides a locked chamber for the reception of the substantial continuous audit or record strip, as shown in Figure 28.
- In this preferred construction, there is provided means for printing the ticket form upon a suitably fed strip of paper. This form is common to all tickets issued by a particular machine and is provided with blank spaces for the reception of specific indicia, selectively variant for each ticket to be printed. Such form is that generally in use, an example of which is indicated by the type-bar or slug shown in Figure 13 wherein the blank form is indicated as containing the name of the station of origin such as "Eau Claire, Wis.", with the words "from" and "to"; the name of the railroad issuing the tickets as for example "issued by C. S. P. M. & O. Ry. Co."; the usual restrictive condition as to continuity of passage and time of commencement of journey, as for example, "Good for one continuous passage commencing not later than one day from date of sale"; the name and title of an official of the issuing railroad, for example, "G. H. MacRae, Gen. Pas. Ag't.;" and the form classification, such as "Form LB1". As noted above, this same form is printed upon each ticket produced by a particular machine, and therefore, a single printing slug only is required. The means which selectively prints the specific indicia upon the paper strip is preferably provided by printing drums upon the periphery of which are borne a plurality of type slugs adapted to print the indicia selected. A blank ticket form is not printed upon the audit strip, but the selected specific data is printed thereon simultaneously with the printing on the ticket strip.
- The printing mechanism and associated parts for the production of the complete ticket slip may first be described. The main shaft 51 extends longitudinally of the machine adjacent the rear portion thereof and suitably borne in each of the plate frames, the plate frames being provided with integral split mountings 52, whereby the frame plates may be clamped to the top rods 36 by means of the screws 53 (see Figures 2, 4 and 5). The crank 41 is operably mounted on the main shaft 51 whereby the main shaft may be manually rotated. The paper from which the ticket slips and the audit record are produced are preferably in strip form, the audit strip being relatively wider than the ticket strip.
- The ticket strip 54 is wound about a spool
- 55 (see Figure 8), and is led up over an

idler 56 journaled in the plate frames. A scoring wheel 57 is rotatably borne by an arm 58, loosely mounted on a set screw 59 having a spring 61 coiled thereon by means of which the scoring wheel 57 is constantly yieldably pressed against the ticket strip which extends therefrom between opposed pairs of paper guides 62 and 63 which are formed of narrow strips of sheet metal and 10 which are carried at their forward ends by means of the shearing block 64. From the forward ends of the paper guides, the paper strip extends over the table plate 65. The platens for securing the impression of the 15 type upon the paper are carried by two parallel platen arms 66 and 67 pivotally borne on the bearing shaft 68 extending across the rear of the machine and carried by the plate frames 45, 46, 47 and 48. The 20 platen arms 66 and 67 carry similar pins 69 to each of which is pivotally secured a link 71. Each link is eccentrically mounted on one of the gears 72 by means of the pivot pins 73. Each of the gears 72 is rotatably mounted on the frame and adapted to be actuated by means of the similar driving gears 74 fast on the main shaft 51.

The means for feeding the paper has 25 operable connection with the platen arms. 30 As here shown, the platen arms 66 and 67 are respectively provided with extensions 75 and 76. Similar links 77 pivotally connect the extensions 75 and 76 with opposed parallel feeding levers 78 pivotally mounted on a stud 79 adjacent the lower portion of the plate frames. These levers are thus simultaneously actuated and carry adjacent their upper ends a clamping means adapted automatically to clamp the paper and upon 35 movement of the lever to carry the paper forwardly, and thereafter to release the same. The fixed member of the paper clamping means is provided by a bar 81 (see Figure 27), the terminal portions of 40 which are downwardly turned and suitably secured to each of the levers 78. Opposed brackets 82 are preferably welded to the opposed inner faces of the terminal portion of the bar 81 and upwardly project to provide a pivotal mounting for the bar 83, which has secured thereon a U-shaped piece 45 of sheet metal, the forward side of which extends below the adjacent side of the bar 83. The edge 84 of this U-shaped metal 50 provides the movable clamping jaw of the paper feeding device. As is indicated in Figures 15 and 16, the U-shaped clamping jaw is yieldably mounted on the bar 83. A 55 simple means of achieving this result is by the provision of a plurality of screws 85 secured to the bar 83, and bearing coil springs 86 upon their stems between their heads and the bar 83. The screws 85 are 60 passed through enlarged apertures in the adjacent face of the U-shaped metal.

Hence, when the movable jaw is pivoted to clamping position, as shown in Figure 16, the edge 84 is yieldably held against the upper surface of the bar 83.

Means are provided so that, when the feeding levers 78 are moved forwardly from their rear position, shown in Figure 5, the jaws will automatically clamp the paper strip therebetween and feed the paper forwardly. A latch 87 is pivotally mounted on one of the levers 78 and normally held in position shown in Figure 5 by means of the coil spring 88. A locking lever 89 is secured to the pivot block 83 and is provided at its forward end with a tooth adapted to engage a complementary recess in the forward end of the latch 87. The locking lever 89 rearwardly terminates in a reduced stem 91 having an inwardly bent terminal portion 92.

Means are provided to rock the locking lever 89 into the position shown in Figure 16 whereby the paper is clamped and the two jaws are held in clamping position by means of the interengagement of the forward ends of the locking lever and latch. As is shown in Figures 4 and 5, a bracket 93 is bolted to the frame 45. This bracket is provided with a forwardly extending surface over which the terminal portion 92 is adapted to travel in its rearward movement from its position shown in Figure 4. Such travel of the terminal portion 92 functions to raise the pivoted cam 94 against the tension of the spring 95 so that the terminal portion 92 will assume the position shown in Figure 5. Forward movement of the lever 78 causes the terminal portion 92 of the locking lever to ride upwardly over the cam surface 96, whereupon the tooth at the forward end of the locking lever 89 is moved into the position shown in Figure 16 and the paper strip is clamped between the bar 81 and the edge 84. The locking lever is thus locked in paper clamping position during the forward movement of the feeding levers, until the pin 97, rearwardly carried by the latch 87, has upwardly moved over the inclined surface of the angled bracket 98 presented in the path of the forwardly moving pin. The bracket 98 is screwed to the frame 45. Travel of the pin 97 over the inclined surface of the bracket 98 rocks the latch 87 and permits release of the locking lever under tension of its coil spring 99, whereby the clamping jaws are opened and the levers 78 may again rearwardly move without affecting the paper strip.

In this selected embodiment of the invention, the ticket form is first printed in blank and the spaces are thereafter filled in by imprint of the selected specific indicia, and therefore the construction and operation of the form-printing mechanism may first be described. As above noted, the ticket strip

is printed so that each ticket slip, after severance from the strip, provides a ticket proper and a check. The form of ticket and complementary check employed in this particular machine is shown in Figure 13, wherein is indicated the type slug employed.

As is shown in Figure 12, the type slug 101 is mounted on a backing plate 102, carried by the opposed form levers 103 which are bent at right angles at their upper ends so that the backing plate 102 may be bolted thereto, as shown. The lower end of the form levers 103 is forked in order that the levers may have a slideable pivotal mounting on the pin 104, carried by the opposed plate frames 45 and 46. The two opposed form levers are driven in timed relation to the platen mechanism by means of a system of levers connected to the platens. These actuating levers connect each platen arm with one of the form levers, and as the systems are similar, it will be necessary to describe but one. As is shown in Figures 4 and 5, a bell crank lever 105 is pivotally mounted on the stud 106, secured to the adjacent plate frame. One end of this bell crank lever is pivotally mounted on the stud 107 carried by the form levers 103 and carries at its other end a pin 108 which effects a pin and slot connection with one end of the bell crank lever 109 pivotally mounted on the stud 111, carried by the adjacent frame 45. The lower end of the lever 109 is pivotally connected by the pin 112 to the crank arm 113, pivotally mounted at its rearward end to the extension 75 of the platen arm 66. Thus, as the platen arms descend, the form levers 103 carry the type slug in an upward curvilinear path into the printing position, shown in Figure 5. The descent of the platen arms 66 and 67 brings the form platen 114 into cooperative printing position. The platen consists of an impression member 115, (see Figure 12) preferably of rubber composition, suitably secured to a metallic backing plate 116 which in turn is secured to, and carried by, the metallic cross bar 117 affixed by the screws 118 to the two platen arms 66 and 67. Elevation of the platen arms similarly causes downward travel of the form levers and printing slug.

In this preferred embodiment of the invention, provision is made for the dating of each ticket at the time of printing of the ticket slip. As is shown in Figure 13, the dating is applied to the ticket and not to the check portion of each form of ticket slip. This dating mechanism is preferably incorporated with the form-printing device, as nearly all the tickets printed during a single day's run of the machine, will bear the same date. A simple means of effecting the dating of the ticket is shown in Figures 12 and 13, wherein the necessary type wheels are shown as comprising a month wheel 119,

a numeral units wheel 120, a numeral tens wheel 121, and a year wheel 122. The peripheries of these wheels extend through an opening provided in the backing plate 102 and type slug 101. Each of such wheels is provided with a complementary dial wheel, whereby the date to be printed may be quickly and easily changed. The month wheel 119 is fast on a shaft 123 journaled at one end in a bracket 124, carried by the backing plate 102. Each of the other three wheels is fast on a sleeve, which sleeves are disposed in superposed concentric relation upon each other. Each bears, at its outer end, a complementary dial wheel fixed thereto. The outer bearing for the dating mechanism is provided by an aperture formed in the right form lever 103.

A simple means of inking the form slug and dating stamp is shown in Figures 5 and 8. It consists of a pair of inking levers 125 pivotally mounted on the opposed frames 45 and forwardly extending therefrom. At the front end a pair of contacting rolls are journaled. Two levers 125 are normally downwardly held by means of the spring 126. The inking roll 127 is thereby tensionably caused to travel across the face of the form slug and dating stamp, as the form levers 103 are moved both to and from operative position. The ink distribution roll 128 is also journaled in the two inking levers and peripherally contacts with the inking roll 127 and functions to supply ink to the working roll 127. As is shown in Figure 5, the axle 129, upon which the inking roll 127 is rotatably carried, is fixed at its opposed ends of the two inking levers 125, while the axle 131 of the distribution roll is mounted in slots 132 formed in each of the opposed levers 125. These two axles are tensionably held together by means of the coil spring 133 so that the distribution roll is constantly tensionably held against the periphery of the inking roll 127.

As above noted, upon the printing of the ticket and check forms, upon the paper strip, the platen arms are elevated, the form slug carriage is rearwardly depressed and the strip-feeding device is moved rearwardly. Upon another descending travel of the platen arms, the strip-feeding device functions forwardly to feed the strip. The timed relation of the travel of the platen arms and feeding device is such that the strip is moved forwardly a distance equal to a ticket slip before completion of the travel of the platen arms. This timed relation is provided so that the strip portion bearing the form will be in proper position to receive the selected destination, fare, etc., indicia in the blank spaces provided on the forms and so that the ticket slip may be completely severed from the strip, preferably just before the indicia printing.

The individual type slugs or bars are movably mounted so that a selected type imprint may be obtained. These type slugs may be mounted upon an endless belt or, 5 as is preferred, may be mounted upon the periphery of a drum. There is here shown a type wheel 134 having the individual type units mounted on its periphery. The type wheel is mounted upon the shaft 135, rotatably borne in bearings provided by the plate frames. It may here be noted that this wheel shaft extends longitudinally of the machine. The type wheel 134 is made fast to this shaft by set screws 136, so that 10 rotation of this type shaft causes a corresponding movement of the type wheel. In the form here shown, the individual type units are integral with a metallic type band 137 extending substantially around the periphery of the type wheel and secured thereto by countersunk screws or rivets. Preferably the type band is provided with a circumferential groove 138 separating each type unit into a printing portion and check 15 printing portion. The ticket printing portion of each type unit bears the name of a destination, fare thereto, name of the issuing railroad, and name of any interline railroad over which travel must be completed beyond the line of the issuing railroad. 20 The check portion bears the destination, i. e., the name of the city or town, and State, and also the name of the issuing railroad. As is shown in Figure 8, the table plate 65 is provided with a longitudinally extending opening 139 through which a longitudinal portion of a positioned severed ticket slip is pressed by means of the front platen. This front platen has an 25 impression member 141, preferably of rubber composition, suitably secured to a metallic backing plate, extending between and terminally secured to the opposed front platen levers 143 pivotally mounted on the platen arms 66 and 67 by the pivot pins 144. The front platen is therefore mounted so that it may be upwardly swung into inoperative position. 30 It is also adapted to be locked in operative position. This locking mechanism is shown in detail in Figure 18, wherein pins 145 are slidably mounted in recesses formed in the opposed ends of the bar plate 142 and are normally tensionably outwardly 35 pressed by means of the compression springs 146 placed in each of the recesses. The outer end portion of the pins 145 are adapted to have locking engagement with holes 147 formed in the outer ends of the platen arms 66 and 67. To facilitate retraction of the pins 145 to release the front platen levers, a handle 148 is secured to each pin 145 and is slidable in an elongated slot 149 in the plate 142.

65 A strip-severing means is carried by the

front platen levers 143 and is cooperable with a shearing block mounted on the plate frames in such manner that the ticket strip is severed before the front platen enters the opening 139, taking a portion of the ticket slip with it. The shearing block 64 is mounted upon suitable extensions upwardly projecting from each of the adjacent plate frames 45 and 46. The knife 151 (see Figure 20) is screwed to a bar 152 pivotally mounted at its ends to the front platen levers 143 by the pivot pins 153. The lower edge 154 of the knife is slightly inclined to the longitudinal axis of the cooperating edge of the shearing block in order to effect 70 a drawing cut. The knife bar 152 is under tension to move the knife edge 154 toward the shearing block. This tension is provided by a compression spring 155, one end of which is secured to the metallic cross bar 117, and the other end portion of which is coiled about a headed pin 156 mounted upon the metallic strip 157, secured to the rear face of the knife bar 152. An adjustable detent is provided to position accurately the knife. This is provided by means of a threaded rod 158 (see Figure 8) received in threaded engagement within the front end portion of the backing plate 116. Preferably the knife is provided with a depending tongue 159 which, as is indicated in Figure 20, is beveled on its rear face. This beveled tongue is adapted, upon descent of the knife, to engage a cam surface 161, on the shearing block 64, so that the 75 knife edge is brought into accurate shearing contact with the front edge of the shearing block. As the knife edge extends below the front platen, it is obvious that the strip will be severed before complete 80 descent of the platen so that a detached ticket slip is provided, the central portion of which may be pressed into printing by the impression member 141, through the opening 139 of the table plate 65.

85 Numbering means are provided by which each ticket slip is numbered. That is, both the check and the ticket are simultaneously stamped with the same numerals. This may be accomplished by any of the common 90 types of numbering machines or counters now in commercial use. Two such counters 162 of the common self-inking type are employed. As is shown in Figures 2 and 4, each of the counters is provided with an 95 operating rod 163, slidably borne in similar brackets 164 provided on the plate frames 45 and 46. These operating rods are connected by similar levers at each side of the type wheel to the extensions 75 of the 100 platen arms 66 and 67. Each counter lever 165 is pivotally connected to one of the platen extensions 75 and 76 by a pivot pin 166 at its rear end, and at its forward end 105

110

115

120

125

130

lever 168, the latter having a pin and slot mounting 169 on its rear end adjacent the plate frame. The forward end of the slotted lever 168 is pivotally mounted on the 5 pin 171 on the bell crank lever 172, having pivotal connection 173 at its lower end to the adjacent plate frame and at its upper end mounted on a pivot pin 174. Thus, at each descent of the platen arms, the 10 tensions 75 and 76 rearwardly travel and effect upward movement of the operating rod 163, whereby the checks and tickets are consecutively numbered.

Means are provided on this machine for 15 picking up the completed ticket slip. The preferred form of such pick-up, is shown in Figures 8 and 19, wherein it is disclosed as consisting of a grip 175 formed of a narrow strip of sheet metal, substantially having the form, in cross section, of a capital letter J. The grip is pivotally mounted on the pin 176 carried by a plate 177 having an angled portion bolted to the backing plate 142 of the front platen. The grip 175 is 20 provided with a transversely extending jaw 178 which is normally tensionably held against the relatively fixed jaw 179 formed at the lower portion of the plate 177. In Figure 8, the grip is shown in such normal 25 position wherein it is maintained by the compression spring 181 secured to the backing plate 142 and to the upper end of the grip 175. In Figure 19, the grip is shown as moved to open position by contact of the 30 curved foot of the grip with the table plate 65. It is moved into such position against the tension of its compression spring. The depression of the substantially central portion of the ticket slip into the opening 139 35 by the front platen, causes the forward portion of the ticket slip to be upwardly curved into such position that the forward edge of the ticket will be presented between the jaws of the pick-up mechanism and 40 clamped upon the raising of the platen arms. As all the printing upon the ticket and check is effected on the under face of the ticket slip, this pick-up mechanism will 45 present the ticket to the machine operator 50 with the printed side facing him.

A dial or index is provided so that the type wheel 134 may be moved into a selected predetermined position in order to cause the printing on the ticket and check 55 forms of certain selected indicia. Such an index is conveniently provided by means of the index wheel 182 (see Figure 7), which is mounted fast on the type wheel shaft 135. Upon the periphery of this index wheel is 60 displayed in alphabetical arrangement, the selected indicia which may be printed by movement of the index wheel. A section of the periphery of this index wheel is shown in detail in Figure 14.

65 Means are provided for inking the type

on the type wheel 134. As shown in Figure 8, a bracket 183 is pivotally mounted upon a pin 184 on each of the opposed extensions 185 of the adjacent plate frames 45 and 46. The rear end of each bracket 183 is 70 downwardly held by means of a tension spring 186 secured to the rear end of the bracket and to the adjacent plate frame. The inking roll 187 is rotatably journaled at its opposed ends in the brackets 183 and 75 is therefore tensionably downwardly held against the type bearing band 137 of the type wheel 134. An ink distribution roll 188 is similarly rotatably borne by the opposed brackets 183 and this roll functions 80 as a reservoir to supply ink to the roll 187.

When it is desired to print from a selected type unit on the wheel 134, such type unit is not directly moved to a position beneath the opening 139 of the table plate; but such 85 selected type unit is moved by means of the index wheel to a predetermined position in front of and below the opening 139, so that, upon actuation of the main shaft 51, the type wheel is moved and the selected 90 type unit travels past the inking roll 187 into inked printing position. This automatic travel of the type wheel from such predetermined position to selected printing 95 position is preferably effected by the mechanism shown in detail in Figures 9 to 11 inclusive.

A gear 191, having a peripheral tooth 100 circumferentially corresponding to each one of the type units on the type wheel 134, is mounted fast on the type wheel shaft 135 and is rotatable by a suitably actuatable dog 192 having a tooth 193 adapted to engage the peripheral teeth of the gear 191. The dog 192 is pivotally mounted by the 105 pin 194 on the bell crank lever 195 freely carried on the type wheel shaft 135. A guide 196 is terminally held to the adjacent frame 46 by the screws 197 and arcuately and upwardly projects adjacent the gear 110 periphery. The tooth is provided with an oppositely projecting extension 198 which is adapted slidably to engage and travel over the inner face of the guide and thereby hold the tooth in mesh with the gear teeth. A seat 199 is provided in the guide 115 adjacent its lower end into which the tooth may be forced to permit free rotation of the gear wheel and type shaft.

Means are provided normally to prevent the tooth from entering such seat. Such means consists of a bifurcated arm 201 (see Figure 10) pivoted to the opposite side of the plate frame 46 and normally held in elevated position by means of the tension spring 202 secured to the arm and to the plate frame. The forks 203 of this arm are thus normally positioned to receive therebetween a pin 204 carried by the tooth. These forks project above and across the 120 125 130

seat 199 and, as the tooth approaches the seat on its downward travel, the pin 204 effectually maintains the tooth in mesh with the gear and prevents seating of the tooth 5 extension.

Driving travel of the toothed dog is effected by movement of the bell-crank lever 195 which at its upper end has connection with the extension 75 of one of the platen 10 arms. Such connection is provided by a lever formed of the two rods 205 and 206.

The rod 205 is pivoted at its forward end on the pin 207 carried by the upper arm of the bell crank lever 195, while the 15 other rod 206 is pivoted at its rear end on the pin 208 carried by the extension 75. The adjacent opposed ends of these rods are both received within a sleeve 209 pinned to, and carried by, the rod 206. A tension 20 spring 211 secured at its ends to the respective rods extends along an elongated recess provided in the sleeve 209. This spring functions, upon rearward travel of the extension 75 and the upward travel of 25 the dog to take up any shock which might be caused by impact of the boss 212 of the lever 195 with its adjustable detent provided by a set-screw 213 received in threaded engagement in an angled portion 214 of the 30 guide 196. A detent to limit the downward travel of the lever 195 is provided by a block 200 screwed to the guides.

Releasing means are provided so that the dog tooth may be held in its seat and free 35 rotation of the gear permitted. A single means of effecting this result is by the provision of a pin 210 on the arm 201 adapted to be engaged by a curved latch 215 fast on a shaft 216 extending across the front 40 of a portion of the machine and pivotally borne by the plate frames 45 and 46. The right end of this latch shaft, adjacent the index wheel, is provided by a handle or finger piece 217 (see Figure 2) by means 45 of which the shaft may conveniently be rocked to cause seating of the dog with resultant disengagement of the gear and type wheel shaft 135 so that the index wheel may be moved to bring a selected 50 type unit to the predetermined position from which it is automatically turned past the inking rolls to printing position upon actuation of the machine. Preferably a mark or other suitable index 218 is provided on a glass portion 219 of the casing adjacent the index wheel whereby there is indicated the particular indicia which would be printed upon the check and ticket forms upon turning of the handle 42.

60 The recording part of this novel machine is to the left of the ticket part when facing the machine. Preferably, this recording part consists of a type wheel mounted for movement simultaneously with the indicia-printing type wheel. As heretofore noted,

the recording of data in regard to tickets issued is made upon a paper strip automatically fed from a spool, under the printing platen, and thence downwardly dropped to the casing interior whereupon 70 it may be periodically removed by auditing officials of the issuing railroad. While, as in the case of the indicia-printing means, individual type bars or slugs may be employed, it is preferred to cast the data-bearing type units on a single cylindrical band. There is diagrammatically indicated in Figure 2, a plurality of data subdivisions transversely extending on each type unit, such, for example, as the number of miles of the 80 journey from the issuing station to the particular destination; the destination, city and state; the abbreviated names of any interline railroads, if any, over which the journey must be completed, the apportioned 85 sums of the total fare earned by each railroad and the war-tax payable by each railroad, and the total fare paid for the ticket in question.

The paper employed for this record or 90 audit strip 221 is proportionately wider than the ticket form strip 54, as shown. This audit strip is provided on a reel or spool 222 mounted between, and rotatably borne by, the adjacent plate frames 47 and 48. 95 The strip is led up over an idler 223 journaled in the plate frames. As is shown in Figure 6, the audit strip passes through a strip guide 224, formed of opposed sheets of metal supported by the plate frames and 100 extending therebetween. The lower sheet 220 of the guide 224 projects beyond the upper sheet and sides of the guide (see Figure 6) and is secured at its forward margin to the opposed plate frames. From the forward end of this guide the audit strip extends upon the upper surface of the audit 105 table plate 225 provided with a central transversely elongated opening, similar to that of the plate 65, through which a transverse portion of the audit strip may be 110 pressed by a suitable actuated platen to cause printing on the strip by the type unit positioned below the opening.

The mechanism for the forward feeding 115 of this audit strip is like the feeding mechanism for the ticket strip and includes the pair of links 77 pivotally connecting the extensions 75 and 76 of the pair of audit platen arms 226 which are pivotally borne 120 by the adjacent portions of the bearing shaft 68 extending across the rear of the machine and borne by the four plate frames. The links at their forward ends are pivotally connected to the opposed parallel feeding levers 78 pivotally mounted on a stud 79 adjacent the lower plate frame 47 and 48. These levers are simultaneously actuated and carry adjacent their upper ends a paper-clamping means 227 which is substantially 130

an elongated duplicate of the ticket strip feeding mechanism and therefore need not be described. The audit strip is therefore fed upon movement of the audit platen 5 arms 226.

Actuation of these audit platen arms is simultaneously with actuation of the ticket platen arms 66 and 67, and the mechanism employed is similar. The audit platen arms 10 226 carry the pins 69 to each of which is pivotally secured one of two opposed parallel links 71. Each link is eccentrically mounted on one of the gears 72 by means of the pivot pins 73. Each of the gears 72 15 is rotatably mounted on the plate frames 47 and 48 and is actuated by the similar driving gears 74 fast on the main shaft 51 extending across the lower rear portion of the machine and borne by the four plate frames. Hence, 20 rotation of the main shaft 51 causes reciprocation of the platen arms 226 and therefore of their extensions 75 and 76 and the feeding levers 78.

As above noted, a single cylindrical band 25 228 peripherally bears transverse individual type-units adapted to print data corresponding to each ticket which is printed simultaneously therewith. This band may be secured by counter sunk screws or rivets to 30 the audit wheel 229 which is fast on the shaft 135 which is freely journaled in the four plate frames and to which shaft are also made fast the type wheel 134 and the index wheel 182. The audit type, ticket and 35 form type, and index are therefore adapted to have accurately corresponding simultaneous movement.

The audit platen arms 226 are, similar to the platen arms 66 and 67, provided with 40 levers 143 pivotally mounted on the audit platen arms and adapted to be swung upwardly into inoperative position or held in downward locked position by means of handles 148 and their slotted pin connection. 45 A similar but elongated impression member 141 is secured to a backing plate 142, carried by the levers 143 and this impression member is adapted upon descent of the audit platen arms, to force the audit strip 221, 50 within the elongated opening provided in the plate 225, so that the audit strip received the type imprint of the specific data carried by the positioned type unit. These audit platen arms, unlike the ticket platen 55 arms, do not bear either the cutting knife or the form printing platen as the audit strip is substantially continuous, i. e. only torn at intervals for purposes of periodic audit, and the form is not printed on the audit strip. 60 Further, a date is not printed upon the audit strip. However, the successive data impressions upon the audit strip are, like successive ticket slips, consecutively numbered—the 65 data on the audit strip bearing the same number as the corresponding ticket slip.

This numbering on the audit strip is effected by means of a numbering device or counter 162 like the ticket slip counters. And, likewise, the audit strip counters are operated from the audit platen arms by a lever system similar to that for operating the ticket counters. In Figure 6, is shown the single counter 162 of the usual self-inking style. The rod 163 thereof is operated from the extension 76 of the adjacent 70 arm 226 by means of the levers 165, 168 and bell crank lever 172.

If desired, the type units of the ticket and check printing device and of the audit printing device may be in the modified form 80 shown in Figures 30 and 31 wherein are disclosed type slugs 231 terminally pinned to opposed links 232 adapted to pass about sprockets 233 fast on the type shaft 135 and about one or more idler sprockets 234 suitably journaled in the adjacent plate frames. Permissible increase of length may be provided by adding other sprockets such as the sprocket 235 shown in dotted lines in Figure 85 90 95 100 105 110 115 120 125 130

Provision is made in this novel machine for power actuation such as by an electric motor 236 suitably mounted upon the machine standard and having suitable worm or gear and pinion power transmission. As shown more particularly in Figures 1, 3 and 23 to 26 inclusive, the motor pinion actuates a gear train 237 journaled on an inclined frame member 238. This train functions as reduction gearing and the final pinion 239 of this train meshes and drives the gear 241 having a hub 242 loose on the main shaft 51 adjacent the right end thereof. This loose gear 241, as shown in Figures 24 and 25, is also adjacent the right one of the four similar driving gears 74 fast on the shaft 51 and respectively in mesh with the gears 72 which actuate the machine mechanism. A clutch mechanism is provided to transmit motion from the gear 241 to the main shaft 51. The relatively fixed member of the clutch is provided by means of a toothed cam disk 243 carried by the hub 242 and rotatable with the gear 241. In the views shown in Figures 23 and 26, this cam disk is driven in a clockwise direction constantly during motor actuation. The teeth of this cam disk are adapted to be engaged by a tooth 244 terminally carried by a relatively movable clutch arm 245 pivotally mounted on a disk 246 fast to the shaft 51 by means of the pin 247. This tooth is under tension of the spring 248 to draw the tooth into engagement with a tooth of the cam disk but is normally detained in the inoperative raised position shown in Figures 23 and 26 by means manually operable by the machine attendant.

The detent 249 is formed by an angled projection from a sector 251 fast on the 130

stud shaft 252 journaled in the upwardly projection frame portion 253 which stud shaft bears fast thereon a knurled disk 254 by which the shaft and sector may be manually rotated to move the detent from operative holding position. The detent is normally held in depressed position by means of the spring 255 secured to the inner face of the knurled disk and to the frame portion 10 253.

The clutch arm 245 is provided with an integral finger 256 having pivotally mounted thereon a substantially U-shaped shoe 257 outwardly held therefrom by means 15 of the compression spring 258 received in a recess in the finger. The shoe is adapted to engage the detent 249 and its resilient mounting absorbs any shock and minimizes noise.

20 Thus the clutch mechanism is normally held in inoperative position while the motor is running. When it is desired to print, the knurled disk is manually turned, against its spring tension, to raise the detent 249 above 25 the path of the finger 256 which is downwardly drawn by the spring 248 so that its tooth 244 may engage the teeth of the driven cam disk 243 whereupon the machine parts are actuated. The knurled disk, after removal of the detent, is released and tensionably returns to normal position in the path 30 of the rotating arm 245 whereby the tooth 244 is again automatically raised to inoperative position after a single revolution of 35 the shaft 51.

Referring to the manual drive of the machine by means of the handle 42: The hub 261 of the crank 41 is mounted loosely on the shaft 51 and is provided with clutch teeth 40 262 to engage similar teeth on the hub 250 which is pinned to the shaft 51. These clutch teeth are normally held in engagement by the spring 263 coiled about the terminal portion of the shaft 51 and held by 45 the cap nut 264 pinned to the shaft. The spring 263 permits disengagement of the clutch teeth 262 while the motor is driving the shaft 51. Provision is made for the release of the detent 249 when the shaft 51 is 50 manually actuated. The crank hub 261 is provided with an integral cam 265 upon which normally rests the lower edge of a cam follower 266 integrally depending from the hub 251 so that, upon rotation of the 55 crank, the follower 266 is sharply raised to cause elevation of the integral detent 249 and the resultant tensioned engagement of the tooth 244 with the disk 243.

I claim—

60 1. A ticket printing machine having in combination means for grasping and feeding forward a paper strip, means to print a ticket form upon the strip including a platen, a shaft and means including an eccentric, and links operable by said shaft to

actuate both said platen and the strip feeding means.

2. A ticket printing machine having in combination, reciprocable means for grasping and feeding forward a paper strip, 70 means to print a ticket and a check form on the strip, means longitudinally to score the strip whereby the strip may be easily separated into a ticket-bearing portion and a check-bearing portion, means selectively to 75 print specific indicia on said strip, and means to actuate both printing means and strip-feeding means whereby the specific indicia is printed on said ticket and check forms. 80

3. A ticket printing machine having in combination, means for grasping and feeding forward a paper strip, means to print a ticket form upon the strip, date-printing means co-operable with said form-printing 85 means coincidently to print a date, means selectively to print specific indicia on said strip, and a shaft to actuate all said printing means and strip-feeding means whereby the specific indicia is printed on said dated 90 ticket form.

4. A ticket printing machine having in combination, means for grasping and feeding forward a paper strip, means to print a ticket form upon the strip, means selectively to print specific indicia on said strip, 95 numbering means co-operable with said indicia printing means coincidently to print a number, and a shaft to actuate all said printing means and strip-feeding means 100 whereby the specific indicia and number is printed on said ticket form.

5. A ticket printing machine having in combination, mean for grasping and feeding forward a paper strip, means to print 105 a ticket form upon the strip, date-printing means cooperable with said form-printing means coincidently to print a date, means selectively to print specific indicia on said strip, number-printing means co-operable 110 with said indicia-printing means coincidently to print a number, and a power shaft to actuate all said printing and strip-feeding means whereby the specific indicia and number are printed on said dated ticket 115 form.

6. A ticket printing machine having in combination, strip-feeding means, means selectively to print indicia on said strip, an index member operable to move the selected 120 indicia to a predetermined position, inking means for said indicia-printing means, and a shaft adapted upon actuation automatically to move the selected indicia past the inking means to accurate printing position 125 and to operate the strip feeding means.

7. A ticket printing machine having in combination, reciprocable means for grasping and feeding forward a paper strip, 130 means to print a ticket form upon the fed

- strip, means operable upon further feeding of the strip to print selected indicia on said printed form; and driving mechanism operable to actuate all said means in timed relation.
8. A ticket printing machine having in combination, a frame, ticket-printing type, a platen co-operable therewith to print a ticket upon a paper strip, platen arms pivotally carried by said frame, strip-feeding means to present a paper strip adjacent said type, a rotary drive shaft connected to the platen arms and the strip-feeding means whereby when the shaft is rotated the strip is fed in timed relation to movement of the platen arms.
9. A ticket printing machine having in combination, ticket-printing type adapted to print a ticket, a platen cooperable with the type, platen arms movable to and from co-operable printing position, and a strip-feeder adapted upon movement of the platen arms toward printing position to grasp and feed a paper strip to printing position, means automatically operable upon arrival of the strip to said position to release the strip and a shaft and connections for operating the platen and feeder.
10. A ticket printing machine having in combination, ticket-printing type adapted to print a ticket, a platen cooperable with the type, pivoted platen arms movable to and from cooperable printing position, strip-feeding levers movable with said platen arms, cooperable clutch members carried by said levers, means automatically operable upon feeding movement of the levers to cause said members to clutch a strip of paper whereby the strip is fed, means automatically operable to cause release of the fed strip and rotary means to operate the platen arms and feeding levers.
11. A ticket printing machine having in combination, ticket printing type adapted to print a ticket, a platen cooperable with the type, platen arms movable to and from co-operable printing position, a knife carried by said platen arms, and feeding means to feed a strip of paper adjacent the type, and a shaft and connections for operating said platen, knife and feeding means in timed relation whereby the strip is fed, thereafter cut and then imprinted.
12. A ticket printing machine having in combination ticket printing type, a platen cooperable with the type, arms carrying the platen and movable to and from cooperable ticket-printing position, and means on the arms to pick up a printed ticket.
13. A ticket printing machine having in combination type adapted to print a ticket upon the under face of ticket material, a platen cooperable with the type, arms carrying the platen and movable to and from cooperable ticket-printing position, and means on the arms to pick up a printed ticket for presentation with the printed face exposed.
14. A printing machine having in combination, a drum rotatably mounted in said machine, type peripherally borne by the drum, a platen movably mounted on the machine to cooperate with the type to print a strip fed therebetween, means to actuate the platen and to rotate the drum from a predetermined selected position to cooperable printing position, and drum-rotating means being releasable whereby the drum may be manually rotated to position a selected peripheral type.

In witness whereof, I have hereunto set my hand this 6th day of July, 1921.

JAMES W. HUBBARD.
